(57) **CLAIM**

The ornamental design for a table tennis table caster beam, as shown and described.

DESCRIPTION

FIG. 1 is a perspective view of the caster beam illustrated in the context of a table tennis table;

FIG. 2 is an outside view of the caster beam of FIG. 1;

FIG. 3 is a top view of the caster beam of FIG. 1;

FIG. 4 is a bottom view of the caster beam of FIG. 1;

FIG. 5 is an end view of the caster beam of FIG. 1, the opposing end is symmetric; and,

FIG. 6 is an inside view of the caster beam of FIG. 1.

The environment shown in broken lines in FIG. 1 is for illustrative purposes only and forms no part of the claimed design.
